DANIEL M. NIXON, OF DANVILLE, ILLINOIS.

Letters Patent No. 77,645, dated May 5, 1868.

IMPROVEMENT IN HAMES.

The Schedule referred to in these Letters Patent and making part of the same.

TO ALL WHOM IT MAY CONCERN:

Be it known that I, DANIEL M. NIXON, of Danville, in the county of Vermillion, and State of Illinois, have invented a new and useful Improvement in Hames; and I do hereby declare that the following is a full, clear, and exact description of the same, reference being had to the annexed drawings, making part of this specification, in which—

Figure 1 is a side elevation, and.

Figure 2 an elevation of the sliding plate.

The same letters indicate the same parts in both figures.

The object of this improvement is to enable the traces to be attached to the hames at various heights, to accommodate the draught to taller or shorter animals. The nature of my improvement will fully appear from the following description and claim.

A is a hames, to which the trace B is connected by a clip, C, on the end thereof, embracing a staple, D, attached to the hames. This staple has shoulders at each end, far enough from the hames to securely and neatly confine the sliding plate F, which has longitudinal slots f f at each end, through which the ends of the staple D pass. A series of projections, E E, is placed on the inner face of the staple D, and corresponding ones, E', are placed on the opposite face of the sliding plate F. The clip C may be supported upon any of these projections. The projections E and E' are opposite one another when the clip is in place, and they hold it in position at the required height. When it is desired to change the height of the clip and trace, it may be done by pressing up the plate F until the points E and E' are brought into the relative positions shown in the red lines. The clip may then be passed between them until properly adjusted, and then the plate be allowed to fall to the position shown in the black lines, the clip resting thereon. The eyes G G are used for the purpose of regulating the length of the hames in adapting them to either a large or small collar.

What I claim as my invention, and desire to secure by Letters Patent, is—

Constructing hames with a staple, D, and sliding plate F, having opposite projections E E', said parts being arranged to adjustably attach the trace, substantially as described.

In testimony whereof, I have signed my name to this specification in the presence of two subscribing witnesses.

DANIEL M. NIXON.
